UNITED STATES PATENT OFFICE.

CLINTON H. HANSON, OF CHICAGO, ILLINOIS, ASSIGNOR TO MOTOR PLAYER CORPORATION, A CORPORATION OF ILLINOIS.

PNEUMATIC-CONTROL VALVE.

Application filed September 16, 1920. Serial No. 410,753.

To all whom it may concern:

Be it known that I, CLINTON H. HANSON, a citizen of the United States, residing at Chicago, in the county of Cook and State 5 of Illinois, have invented a certain new and useful Improvement in Pneumatic-Control Valves, of which the following is a full, clear, and exact description, reference being had to the accompanying drawings.

10 The purpose of this invention is to provide a controlling device for governing the volume of air caused to be drawn through the tracker bar of a player piano. In the operation of the player piano it is customary 15 to provide a suction device connected with the various pneumatics for actuating the keys. This invention is adapted for use with a suction device in the nature of an electric motor and rotary fan enclosed in the casing 20 and adapted to create a partial vacuum for actuating the pneumatics. When the motor is running in such casing it is necessary that air be passed around and through the same in order to avoid excessive heating. It is 25 also desirable that this be in part at least of the same air which is drawn through the actuators of the piano, thereby affording economy both in construction and operation. When such a motor is running for operating 30 the suction device, a substantially constant pressure vacuum is maintained. In many instances no provision is made for the tone gradation, that is, whereby the keys are struck forcibly or lightly to give loud or 35 soft tones. Accordingly one of the purposes of this invention is to govern the amount of air drawn through the pneumatics to the suction device and so arrange this governing device that when the air from the pneumatics 40 is partially shut off, a corresponding amount of air will be drawn from an outside source through the motor, whereby cooling of the motor is assured, thus avoiding the necessity of varying the speed of 45 the motor.

In carrying out this object, I have provided a control valve in a passage leading from the pneumatics of the piano to the suction device, and in this passage I have provided 50 between the valve and the suction device a supplemental air inlet, which is normally closed by a member yieldingly urged to its closed position, but adapted to automatically open upon the increase of suction, due 55 to the closing or partial closing of the above

mentioned valve (in the passage leading from the pneumatics). Thus the volume of air creating the tones may be varied at will by actually shutting off the passage through which it flows, and at the same time an automatic device permits a substantially normal volume of air to pass through the suction device into the motor. 60

Still another object is to so arrange this control valve that it is adapted for connection with pneumatic controlling devices governing the operation of the player piano, such for example, as a pneumatic controlling the rewinding of the player roll and a pneumatic governing the switch for the motor of the suction device. 65 70

The drawings hereof illustrate a preferred embodiment of my invention, and the above and other objects will be made more clear in the following description which relates to 75 the drawings. The essential characteristics of my invention are hereinafter summarized in the claims.

In the drawings Fig. 1 is a front elevation of a player piano equipped with my 80 invention; Fig. 2 is an enlarged detail showing the upper portion of the suction device to which my pneumatic controlling device is attached; Fig. 3 is a plan of the pneumatic controlling device on a still further enlarged scale; Fig. 4 is a vertical section through the same; Fig. 5 is an enlarged detail illustrating the opening of the supplemental air valve; Fig. 6 is a somewhat diagrammatic view in the nature of 85 a plan of the suction device and controlling means, showing an arrangement of connections with pneumatics governing the operation of the player piano; Fig. 7 is a side elevation partly in section of a suction device embodying my invention. 90 95

As illustrated in Fig. 1, the suction device with which my invention is particularly adapted for use may be attached beneath the key board of a piano, designated A, and arranged to be concealed by the usual vertical panel beneath the key board. The device is indicated at 1, as suspended on resilient supporting straps 2, and as having a main connection 5 leading from the usual air chest 6 to the suction device. This air chest 6 is connected, of course, with the tracker bar over which the player roll 7 passes, governing the various pneumatics actuating the keys of the piano. A cord designated 8 100 105 110

may contain the electric wire for connecting the suction device with any standard electrical plug or socket connection. In the device illustrated in Fig. 7, a motor indicated in general at 3 is employed for actuating fan blades indicated 4, which are mounted on the armature shaft 9.

The apparatus as briefly described, is related particularly to the use of a suction device such as shown, described and claimed in patent to G. W. Garman, No. 1,320,224, granted October 28, 1919, though of course the present invention is not limited to use with any particular construction of suction device proper.

The passage leading from the air chest to the suction device may comprise any suitable tube connected with a tubular extension 10, joining a chambered body member 12, flanged at 13, and secured to a cover member 14 of the suction device, through which an opening 15 is formed to complete the inlet to the suction device. Mounted in the tubular extension 10 is shown a butterfly valve 17, mounted on a rock shaft 16 extending outside of the passage through bearings indicated at 18, and turned upwardly to form a rock arm 20. Connected on the rock arm 20 by a pivot screw 22 is shown a block 24, in turn adjustable by means of a screw 25 along an actuating rod 26. This rod is shown connected with one of the control levers at 30, usually provided at the key board of the piano; the rod being connected to the lower end of the lever may be controlled manually while operating the piano, or may be set in a given position, thus moving the butterfly valve to any position from full open to full closed.

Intermediate the butterfly valve and the aperture 15 of the suction device is a spring operated valve comprising a plate 32, a rod 33 and a spring 34. The periphery of the plate extends beneath the inner edge of a flanged member or cover plate 35, which as shown in Fig. 4, may be secured to the top of the chambered body member 12. This cover plate 35 is preferably an annular member having a diametrically positioned connecting bar 36, thus forming a spider in which the rod 33 is slidably mounted. A layer of porous fabric, preferably piano felt 37, extends across the annular cover plate 35 and serves somewhat in the nature of a gasket, while another layer of felt 38 is secured to the upper surface of the plate 32 and is adapted to be held in abutting engagement with the layer 37. A stop collar 39 may be adjusted by the set screw 40, and may abut one end of the spring 34, whereby the fabric layer 38 is constantly urged toward the layer 37.

Since the butterfly valve is manually operable, the pressure in the tube between the tracker bar and the butterfly valve may be

varied at will. However, the pressure in the chamber intermediate the valve and the suction device is adapted to remain constant by reason of the fact that the spring actuated valve counterbalances any variation in pressure that may be effected by the manual operation of the butterfly valve. Whenever the butterfly valve is moved to a closed or partially closed position, the vacuum in the chambered member increases to an extent sufficient to overcome the tension of the spring 34, thereby causing the plate 32 to be moved downwardly and air to be sucked into the chamber through the porous layer 37. Fig. 5 is a detail view showing the plate in a lowered position, and in this view the arrow indicates the path of the incoming air. With such an arrangement then, the amount of air passing through the chambered body and, therefore, through the suction device remains substantially constant, and is not materially affected by variations in the volume of air passing through the tracker bar.

Leading from the constant pressure chamber 12, there are two outlet members 41 and 42, one of which leads to a pneumatic mechanism indicated generally at 43, while the other outlet may lead to a pneumatic cutoff switch 44. The rewinding mechanism 43 is contained within the housing 46 and is operable by the passage of air through tubes 45 and 47 which are arranged to be connected with the tracker bar and the constant pressure chamber, respectively. Since the tube 47 leads into the constant pressure chamber 12, the pneumatic rewinding motor is set in motion whenever the aperture in the tracker bar, to which the tube 45 is connected, is uncovered, in the usual manner, that is, when the player roll is entirely un wound.

The automatic cutoff switch is also provided with a tube 48 which may be operatively connected to an aperture in the tracker bar. A pneumatic bellows 49 may be positioned on the housing 50, and be operated by the air passing through the tube 48, the tube 51 and the constant pressure chamber 12. Whenever the bellows is compressed, a cutoff rod 52 is moved downwardly to actuate a switch within the member 44. This switch is connected in series with the lead lines 8 to control the operation of the suction device. The cutoff switch is actuated whenever the aperture to which the tube 48 is connected is uncovered, and this is effected whenever the rewinding mechanism removes the roll from contact with the tracker bar.

In operation, the operator inserts the player roll in the customary manner and covers the tracker bar with a part of the roll before starting the motor, and a suitable switch is turned to start the suction device, whereupon the roll is pulled across

the tracker bar and the pneumatics of the piano actuated through the lead tube 5. While the roll is in operation the force with which the pneumatics are actuated may be controlled by movement of the hand lever 30. When the hand lever 30 is moved the butterfly valve 17 is moved accordingly to restrict the passage in the tube extension 10. Assuming that the butterfly valve is turned to a partially closed position, then the vacuum produced within the chamber 12 tends to rise and to overcome the tension in the spring 34. When the tension in the spring is overcome, the plate 32 is forced downwardly and air is admitted into the chamber 12 through the porous material 37. By regulating the tension in the spring 34, the auxiliary valve may be so adjusted that any manipulation of the lever 30 causes instant effect upon the actuating pneumatics of the piano. When the roll is entirely unwound, air passes through the tube 45 and causes the rewinding motor to be set in operation, and as soon as the rewinding mechanism has entirely removed the roll from the tracker bar, air passes through the tube 48 and cuts off the current to the motor which operates the suction device.

From the foregoing description, it will be seen that I have provided a device which is capable of varying the pressure on the actuating pneumatics of a piano without decreasing the volume of air which passes through the suction device; that I have provided a rewinding mechanism and an electric switch which may be operated independently of the pressure acting upon the actuating pneumatics of the piano, and that I have provided a mechanism which may be attached to any manually or electrically operable suction device.

Having thus described my invention, I claim:

1. In a suction mechanism for operating a player piano, an electrically driven motor and fan suction device, means whereby the air impelled by the fan is caused to flow past the motor for cooling purposes, a hollow member attached to the suction device, a tube projecting laterally from the member and connected with the wind chest of the player piano, means for closing the passageway in the tube by varying degrees and a yieldingly operated valve opening to the atmosphere intermediate said means and the suction device, whereby the air passing through the device remains constant in volume independently of the volume of air flowing through said wind chest.

2. In a suction mechanism for operating a player piano, the combination with an electrically driven motor and fan suction device having an inlet aperture adjacent the top thereof, of a hollow member positioned over the aperture and having a passageway lead-

ing to the wind chest of the player piano, a valve for varying the pressure in the passageway and means connected with the keyboard of the piano for manually operating said valve, whereby the air passing through the device remains constant in volume independently of the volume of air flowing through said wind chest.

3. In combination, a suction device, a flanged member rigidly secured to the device and having a passageway leading to the wind chest of a player piano, means for manually varying the volume of air flowing thru the passageway, said member having an aperture intermediate the valve and the suction device, and yielding means for normally effecting a closure of the aperture, said last mentioned means being operable to permit a constant volume of air to pass thru the suction device.

4. In combination, a suction device, means carried by the device for connecting it to the wind chest of a player piano, means for manually controlling the air passing thru said connection, a valve, a spring for normally holding the valve in a closed position, means for adjusting said spring whereby the valve may be opened to permit a constant volume of air to pass thru the suction device, whenever the manually operable means restricts the volume flowing thru the connecting means.

5. In a suction mechanism for operating a player piano, the combination with an electrically driven suction device, of a casing having an aperture therein and positioned across the inlet port of said device, said casing having a passage leading therethrough and connected with the tracker bar of a player piano, and having an opening leading directly to the outside air, a valve mounted in said casing, said valve comprising a flat closure member inside the casing, a layer of porous material rigidly secured to the inner wall of said casing, and means for constantly urging the closure member against the layer of porous material, whereby a constant volume of air is caused to flow through the suction device independently of the volume flowing through said passage.

6. In a suction mechanism for operating a player piano, the combination with a suction device embodying a motor and fan unit, said device having an aperture therein leading to the atmosphere and having an opening therein connected with the tracker bar of a player piano, a member extending across said aperture and projecting from the device, a plate associated with said member, means for holding the plate in abutting engagement with the member, said means being actuated to move the plate inwardly by the difference in air pressure between the interior and exterior of said member.

7. In a suction mechanism for operating a player piano, the combination with a suction device having an opening leading to the atmosphere and having an aperture connected with the tracker bar of a player piano, of a valve for normally closing said opening, said valve comprising a spindle, a plate, a layer of porous material between the spindle and plate, and a spring for holding the plate in abutting engagement with the spindle.

8. In combination, a wind chest, a suction device connected therewith, a hollow casing intermediate the wind chest and the suction device, said casing having passages leading therefrom, one of said passages being connected with a rewinding mechanism.

9. In combination, a suction device, a tube extending therefrom and connected with the operating pneumatics of a player piano, a member intermediate the tube and the suction device, said member having a constant pressure chamber, tubes leading therefrom, one of said tubes being connected with a pneumatic switch.

10. In combination, a suction device, a hollow member connected thereto, passages leading from said member, one of said passages being connected with the wind chest of a player piano, another of said passages being connected with a pneumatic switch, means for varying the pressure in the passage connected with the wind chest, and means for maintaining constant pressure in the passage to which the switch is connected.

11. In combination, a suction device, a member connected thereto, passages leading from said member, one of said passages being connected with the wind chest of a player piano, another of said passages being connected with a pneumatic rewinding mechanism, means for varying the pressure in the passage connected with the wind chest, and means for maintaining constant pressure in the passage to which the rewinding mechanism is connected.

12. In combination, a fan suction device, a hollow member carried thereby, said member comprising a body portion having an aperture leading to the atmosphere, a passage leading from the body portion and connected with the wind chest of a player piano and means for manually controlling the pressure in said passage, and means for effecting a yielding automatic closure over the aperture for permitting a constant volume of air to pass through the device independently of the volume of air flowing through said passage.

13. In combination, a hollow casing connected to a suction device, said casing comprising a body portion having an aperture therein, means for maintaining a constant pressure within the casing, a passage leading from the body portion and connected with

the wind chest of a player piano, means for varying the pressure in said passage, and tubes leading from the constant pressure casing to a pneumatic switch, and a rewinding mechanism respectively.

14. In combination, a casing rigidly connected to a suction device, said casing having an aperture therein leading to the atmosphere, means comprising a spring actuated valve normally effecting a closure over said aperture, a tube leading from said casing and connected to the wind chest of a player piano, a valve intermediate the casing and the wind chest, means for manually operating the last mentioned valve.

15. In combination, a casing connected to a suction device, means comprising a spring actuated valve for permitting a constant volume of air to pass thru said casing, a tube leading from said casing and connected to the wind chest of a player piano, a manually operable valve intermediate the casing and the wind chest for varying the volume of air passing thru the tube, and passages leading from said casing, intermediate the manually operable valve and the suction device, to a pneumatic switch and rewinding mechanism respectively.

16. In combination, a suction device, a housing having a flanged body portion for securing it to the suction device, a passage leading from said housing and connected with the wind chest of a player piano, a valve intermediate said housing and the wind chest, means for manually operating the valve, said housing having an aperture to admit air into the suction device, means for normally closing said aperture, tubes leading from the body portion, means for connecting one of said tubes with a rewinding mechanism, and means for connecting another of said tubes to a pneumatic switch.

17. In combination, a suction device, a hollow member having a flanged body portion for securing it to the suction device, a passage leading from said member and connected with the wind chest of a player piano, a valve intermediate said member and the wind chest, a lever carried on the keyboard of the piano and connected with said valve, said member having an aperture to admit air into the suction device, a porous diaphragm for normally closing said aperture, a pressure actuated valve engaging said diaphragm, and tubes leading from the body portion, one of said tubes being connected to a pneumatic switch.

18. In combination, a suction device, a hollow member connected therewith, a passage leading from the member and connected with the operating pneumatics of a player piano, a valve within the passage, means for manually controlling the valve, said member having an aperture intermediate

- the valve and the suction device to admit air therein, a layer of porous material extending across the aperture, a plate adapted to abut said layer, means for constantly urging said 5 plate against the layer and tubes leading from the body portion and adapted to be connected with a rewinding mechanism and a cutoff switch, respectively.
19. In combination, a suction device, a 10 casing connected thereto, a passage leading from the member and connected with the operating pneumatics of a player piano, a valve within the passage, a lever, a pitman connecting the lever with the valve, said member having an aperture intermediate the
- valve and the suction device to admit air therein, a layer of porous material extending across the aperture, a plate adapted to abut said material, a spring for constantly urging said plate against the material, an adjusting 20 collar abutting said spring and passages leading from the body portion and adapted to be connected with a rewinding mechanism and a cutoff switch respectively.
- In testimony whereof, I hereunto affix my 25 signature.

CLINTON H. HANSON.
